Patented Aug. 12, 1919.

Inventor
Robert A. Cashen
by Seymour Pearce, Atty.

UNITED STATES PATENT OFFICE.

ROBERT A. CASHEN, OF MERIDEN, CONNECTICUT.

RADIATOR-CAP.

1,312,892.

Specification of Letters Patent. Patented Aug. 12, 1919.

Application filed April 16, 1919. Serial No. 290,523.

To all whom it may concern:

Be it known that I, ROBERT A. CASHEN, a citizen of the United States, residing at Meriden, in the county of New Haven and State of Connecticut, have invented a new and useful Improvement in Radiator-Caps; and I do hereby declare the following, when taken in connection with the accompanying drawings and the characters of reference marked thereon, to be a full, clear, and exact description of the same, and which said drawings constitute part of this application, and represent, in—

Figure 1 a side view of the upper end of a radiator neck with my improved cap connected therewith.

Fig. 2 a plan view of the cap band detached.

Fig. 3 a side view of the filler closing cap.

Fig. 4 an underside view of the same.

Fig. 5 a plan view of the cap strap detached.

This invention relates to an improvement in radiator caps for automobiles. In the more general construction these caps are screwed into the filling neck of the radiator. When unscrewed they are liable to be dropped and difficulty is sometimes experienced in unscrewing. The object of this invention is to hinge the cap to the filling neck so that it may be readily interlocked therewith and the neck opened when desired, and the invention consists in the construction hereinafter described and particularly recited in the claim.

The usual neck 6 has a collar 7 slightly larger in diameter than the neck so as to form a shoulder 8 between them. Clamped

around the neck beneath the collar is a band 9 formed from a strip of metal the ends extended upward forming arms 10. The band is secured around the neck by means of a bolt 11 and the upper ends of the arms are secured by a bolt 12 which also passes through the end of a cap strap 13 which is turned at right angles to the main portion of the strap, which is secured to a cap 14 formed from any suitable material and adapted to enter the collar 7 so as to close the filling opening. The strap also extends downward and is formed with a shoulder 15 adapted to spring under the lower edge of the collar 7 beyond which it projects to form a finger-piece 16. The strap is thus hinged to the collar, is always ready in position, and when closed is securely locked in place.

I claim:

The combination with a filling neck formed with a collar, a band secured to the neck below said collar, the ends of the said band formed with upwardly projecting integral arms, a strap having one end turned at right angles to the plane of the strap and secured to the upper ends of said arms, a cap secured to said strap and adapted to enter said collar, said strap formed with a shoulder adapted to engage with said collar when the cap is in place.

In testimony whereof, I have signed this specification in the presence of two subscribing witnesses.

ROBERT A. CASHEN.

Witnesses:

BERNARD J. GLEASON,
THOMAS HOBAN.
